HEEL FOR BOOTS AND SHOES

Filed Feb. 20, 1945

Inventor,

Francis Ward,

By Frank S. Appleman,

Attorney.

3

Referring to Figures 5 to 8 in the example shown therein a plate 15 shaped to suit the peripheral contour of the top piece end of the heel *a* is formed with a flange 15a and with a number of apertures 16. At the top piece end the heel *a* is formed with a rabbeted edge 17 to receive the flange. Thus when the plate is applied to the heel it fits snugly thereon with its inner face in contact with the surface 18 of the top piece end of the heel, as shown in Figure 7. The plate 15 is formed with countersunk holes 19 through which wood screws 20 are inserted to fix the plate 15 in position. When the top piece 11 is applied the attaching slugs (one of which is represented at 12) or nails are inserted into the exposed portions 18a (see Figure 6) of the surface 18.

As will be appreciated, a plate formed with two or more than three apertures may be provided if desired.

In the constructions shown in Figures 3 and 7, the heel has a covering 13, which may be of leather, fabric, Celluloid or like pliable material, and the edge of the covering at the top piece end is inturned over the plate, as represented at 14, so as to be secured between the plate and the top piece 11 when the latter is applied. Alternatively the heel may be covered first and the plate may be attached afterwards so that the said edge of the covering is located between the plate and the heel, and the plate is exposed.

The plate may consist of any suitable metal, fibre, or of any of the now well known thermo-setting or thermo-plastic (synthetic) substances, cast, pressed or moulded to shape, according to the nature of the material, or substance. Plates of various colours may be provided so that when a plate is exposed as aforesaid it harmonizes or contrasts with and enhances the appearance of the heel.

The invention may also be applied to heels with a cellulosic or other conventional finish as distinct from being covered, and to heels made of thermo-setting or thermo-plastic substances covered or otherwise suitably finished.

In the case of a plastic plate the latter may be stuck on to the heel by means of a plastic or other cement, instead of or as well as being otherwise secured.

What I claim then is:

1. In combination, a solid heel the outer end of which is formed with a rabbeted edge, a member shaped so as to fit within the said rabbeted edge and surround the heel, and a top piece secured to the outer end of the heel by elements driven into the latter, the aforesaid member serving to prevent the heel from splitting when the elements are driven in.

2. In combination, a solid heel the outer end of which is formed with a rabbeted edge, a plate having therein at least one aperture and shaped at its periphery so as to fit within the said rabbeted edge and surround the heel, and a top piece which is secured by elements driven into the heel through the aperture, the peripheral portion of the plate serving to prevent the heel from splitting when the said elements are driven in.

4

3. In combination, a solid heel, a top piece attached to said heel by elements driven into the end of the latter, and, between the heel and the top piece, a plate formed with at least one aperture and fitted to the top piece end of the heel which is rabbeted at the edge to receive it, said plate and top piece end being, moreover, so formed that the outermost surface of the plate lies flush with the corresponding surface of the heel, and the plate serving to prevent the heel from splitting when the aforesaid elements are driven into it.

4. In combination, a solid heel, a top piece attached to said heel by elements driven thereinto, a plate secured between the heel and the top piece, said plate being formed with at least one aperture and fitted to the top piece end of the heel which is rabbeted at the edge to receive it, the plate serving to prevent the heel from splitting when the elements are driven in, and a heel covering the edge of which at the said top piece end is inturned over the plate so as to be secured between the latter and the top piece.

5. In combination, a solid heel, a peripherally flanged plate formed with at least one aperture and fitted to the outer end of the heel which end is formed with a rabbeted edge to receive the flange suchwise that the innermost surface of the plate is in facial contact with the opposing surface of the said end of the heel, and a top piece which is secured by elements driven into the heel through the aperture, the flanged portion of the plate surrounding the heel and preventing it from splitting when the aforesaid elements are driven in.

6. In combination, a solid heel, a peripherally flanged plate formed with apertures and holes, said plate being fitted to the outer end of the heel which end is formed with a rabbeted edge to receive the flange suchwise that the innermost surface of the plate is in facial contact with the opposing surface of the said end of the heel and being, moreover, attached to the heel by securing elements inserted through the aforesaid holes, and a top piece which is secured by elements driven into the heel through the apertures, the flanged portion of the plate surrounding the heel and serving to prevent the heel from splitting.

7. In combination, a solid heel, a peripherally flanged plate formed with apertures and holes, said plate being fitted to the outer end of the heel which end is formed with a rabbeted edge to receive the flange suchwise that the innermost surface of the plate is in facial contact with the opposing surface of the said end of the heel and being, moreover attached to the heel by securing elements inserted through the aforesaid holes, a top-piece which is secured by elements driven into the heel through the apertures, the plate serving to prevent the heel from splitting when the last mentioned elements are driven in, and a heel covering the edge of which at the top piece end is inturned over the flanged plate so as to be secured between the latter and the top piece.

FRANCIS WARD.
